UNITED STATES PATENT OFFICE.

MELCHIOR BRAZEAU, OF MONTREAL, QUEBEC, CANADA.

PICKER.

SPECIFICATION forming part of Letters Patent No. 272,118, dated February 13, 1883.

Application filed August 28, 1882. (Model.) Patented in Canada July 26, 1882, No. 15,199.

To all whom it may concern:

Be it known that I, MELCHIOR BRAZEAU, a citizen of the Dominion of Canada, residing at the city and district of Montreal, in the Province of Quebec, have invented certain new and useful Improvements in Pickers, (for which I have obtained a patent in Canada, No. 15,199, bearing date 26th July, 1882,) of which the following is a specification.

10 The object of my invention is to produce an instrument that will permit any one to pick out, lay hold on, remove, place, and replace small articles in any place whatever—as, for example, to pick out in a shop-window a designated article and replace it afterward to its former place without disturbing anything else, which ordinarily in such a case is a very difficult task without the use of my instrument.

15 In the annexed drawings, Figure 1 represents an elevation of my instrument. Fig. 2 represents a vertical section of my instrument, showing the different parts and their assemblage. Fig. 3 is a vertical section of the handle of my instrument, shown on a larger scale.

20 My instrument is composed of two principal parts, A and B, Figs. 1 and 2, made of wood or metal, joined together from C to D, and retained into position by the movable ferrules or rings C and D, the said parts A and B forming the body of my instrument. The parts A and B are made thinner at their extremities F F, and affect the form of pinchers. The double ferrule G, through which pass the branches E E, and which is also movable, has for its object to regulate the distance between the pinchers according to the size of the article to be removed. The fixed ferrule D incloses and retains the lower extremities of the parts A and B at its upper part, and has also for its object 25 to permit the sliding of the handle H at its lower part.

Fig. 1 represents my instrument in its normal position—that is to say, when not working.

30 Figs. 1 and 2, represents a string, either metallic or made with hemp, the extremities of which are secured to the pinchers F F at a and a'. This string, crossing at I', goes down on both sides and on the inside of the branches

E E, passes through the whole length of the portion A B and the handle H, and also passes freely through the ring J, which is secured to the handle H by the button K, Figs. 1, 2, and 3. The said string I goes down along the branches E E A B and follows the longitudinal grooves L L, Fig. 2. The said string I is also retained in said grooves L L by the catches b b'. By such an arrangement it is almost hidden from view. These catches b b' could be easily replaced by small pulleys, which would facilitate the sliding of the string. The pinchers F F are provided with pieces of glued chamois, leather, cloth, or india-rubber, M M, secured on the internal sides, the object of which is to prevent the slipping of the articles 35 to be removed, and also to preserve them from deterioration in any way.

The instrument represented in Fig. 3 is provided with a longitudinal opening, f, through which passes the string I. The string passes 40 around the catch J at I' and works freely around said catch. When said handle H is brought by the hand to the position indicated by Fig. 2 the catch J is maintained and secured to the button K at g g. When the handle H 45 is pulled the string I slides along the branches E E, and the pinchers are brought one against the other symmetrically to catch the desired article.

Thus the mechanism and working of my instrument is simple and easily understood. A single person is needed to operate with it. All dimensions can be given to it, according to circumstances. It is light, easily transportable, and of an incontestable utility.

Having described my invention, what I claim, and desire to secure by Letters Patent, is—

In a picker, the combination of the branches A B E E F F, the ferrules G, C, and D; the handle H, string I, catches b, b', and J, cushions M M, and button K, all as above described, and for the purposes set forth.

MELCHIOR BRAZEAU.
